DESIGN FOR A PORTABLE SODA FOUNTAIN

Joseph R. Lewis, Burbank, Calif.

Application September 17, 1945, Serial No. 122,115

Term of patent 14 years

(Cl. D14—3)

To all whom it may concern:

Be it known that I, Joseph R. Lewis, a citizen of the United States, residing in Burbank, in the county of Los Angeles and State of California, have invented a new, original, and ornamental Design for a Portable Soda Fountain, of which the following is a specification, reference being had to the accompanying drawing, forming part thereof.

Fig. 1 is a top plan view of a portable soda fountain, showing my new design.

Fig. 2 is a side elevational view.

Fig. 3 is a rear elevational view, partly broken away.

Fig. 4 is a front elevational view, to a reduced scale.

The side of the portable soda fountain which is opposite to the side shown in Fig. 2 is substantially plain and unornamented. The dominant features of the design are embodied in the parts shown in full lines.

I claim:

The ornamental design for a portable soda fountain, substantially as shown and described.

JOSEPH R. LEWIS.
